J. C. DEAGAN.
MUSICAL INSTRUMENT.
APPLICATION FILED SEPT. 4, 1913.

1,104,478.

Patented July 21, 1914.

Witnesses:

UNITED STATES PATENT OFFICE.

JOHN C. DEAGAN, OF CHICAGO, ILLINOIS.

MUSICAL INSTRUMENT.

1,104,478.

Specification of Letters Patent. Patented July 21, 1914.

Application filed September 4, 1913. Serial No. 788,095.

To all whom it may concern:

Be it known that I, JOHN C. DEAGAN, citizen of the United States, residing at Chicago, in the county of Cook and State of Illinois, have invented a certain new and useful Improvement in Musical Instruments, of which the following is a full, clear, concise, and exact description, reference being had to the accompanying drawings, forming 10 a part of this specification.

My invention relates to musical instruments and has a number of objects and advantages in view, though certain of the novel characteristics herein disclosed, including the construction of sounding bars and the construction of sectional resonating tubes, are claimed in my copending applications Serial No. 807,663, filed December 19, 1913, Serial No. 807,664, filed December 19, 20 1913, and Serial No. 818,773, filed February 14, 1914.

I will explain my invention fully by reference to the accompanying drawing showing the preferred embodiment thereof and in 25 which—

Figure 1 is a plan view of a musical sound producing element constructed in accordance with my invention, a portion of another sound producing element entering into the 30 formation of a musical instrument being indicated; Fig. 2 is a sectional view on line 2 2 of Fig. 1; Figs. 3 and 4 are sectional views illustrating differing positions of adjustment of a part of the structure illustrated in Figs. 1 and 2; Fig. 5 is a view in the direction of arrow 5 in Fig. 2; Fig. 6 is a sectional view on line 6 6 of Fig. 2; and Fig. 7 is a view illustrating a modification.

Like parts are indicated by similar characters of reference throughout the different figures.

The sound producing elements shown are in the shape of sounding bars 1 which may be struck by an operating hammer in order 45 to set them into sound producing vibration. The sounding bars of wood or metal have their top and bottom sides symmetrically concave as illustrated at 2 in Fig. 2, sound-producing vibrations emanating freely from 50 both sides of the bars owing to the symmetrical distribution of the sound producing mass.

Any suitable means for suspending the 55 sound producing bars may be employed such, for example, as cords 3 strung through supporting ears 4 and end portions of the

bars 1, the strings being tied at 5 to hold the bars in the desired positions. Resonating tubes 6 of any suitable formation are perpendicularly disposed with respect to the bars 1 and underlie their middle portions whereby the sound waves emanating from the bars may enter the tubes. A number of these bars which are capable of producing the tones of a musical scale together with their resonating tubes are generally supported side by side longitudinally of the instrument and in close proximity. Sound waves are liable to enter the tubes from adjacent tubes through the upper ends thereof and in order to reduce this action the upper ends of the tubes are desirably provided with caps 7 which are slotted at 8, these slots extending longitudinally of the bars 1 and transversely of the instrument as a 75 whole, this characteristic being set forth in my co-pending application Serial No. 807,664, filed Dec. 19, 1913. Slots 8 are provided in the caps 7 and extend longitudinally of the sounding bars under which the caps are disposed, each slot 8 having a slot 9 that preferably constitutes a continuation of the slot 8 and is located in the portions of the resonating tubes which face a side of the instrument.

The tubes are desirably formed in telescoping sections whereby the length thereof may be adjusted to bring the sounds emanating from the tubes into tune with the sounds initiated by striking the sounding bars, the tonal adjustment secured by adjusting the parts of each tube being secured by means of a clamping screw 10 in clamping connection with ears 11 that are upon opposite sides of a slot 12 in the outer telescoping tube section. Fig. 5 illustrates a number of horizontal lines which are marked "low pitch" "warm" "medium" "cold" "high pitch" with which the bottom edge of the outer telescoping tube section 100 may be brought in register to regulate the pitch of the tone issuing from the tube. The tube itself may be of any suitable formation, though I have shown an improvement in resonating tubes in Figs. 2, 5 and 6 where there is shown a characteristic having some of the features which are disclosed in my Patent 747,340, issued December 15, 1903 and relating to musical instruments.

In Figs. 2, 5 and 6 the length of the air 110 column is increased by means of a longitudinally disposed partition 13 and a trans-

verse continuation thereof indicated at 14 whereby there is formed a supplemental tubular length, the partition 13 terminating sufficiently above the closed bottom 15 of 5 the tube so that the sound may be freely propagated through the increased length of the air column thus provided. In order to reduce the return or reflection in the tube of the sound directed downwardly into the 10 tube the bottom 15 of the tube is made semi-globular, the partition 13 terminating at its lower end substantially at the center of the semi-globular end piece 15 whereby the sound wave will smoothly round the passage 15 into the portion of the air column at the lower part of the tube and to the right of the partition 13. Further to promote the desired passage of the sound waves around the bottom of the tube the lower margin of 20 the partition 13 is desirably rounded as indicated at 16, such rounding being formed by a small cylinder or curved body extending diametrically of the tube where the partition 13 terminates.

25 Still referring more particularly to Fig. 2, I have provided the resonating tube with a sound wave conducting outlet that is in the form of a bore of a pipe portion 17 which bore communicates with the upper end of 30 the lower branch of the air column within the tube. Referring now also to Figs. 3 and 4, the element 17 has a reduced outer end 18 upon which a cap 19 is threaded, this cap having a knurled flange 20 by which it may 35 be turned along the pipe portion 18. The cap 19 supports a vibrant diaphragm 21 which is to vibrate in correspondence with the vibrations of the sound waves and the extent of whose vibration is to be determined 40 by turning the cap upon the threaded extension 18 so as to vary the degree of pressure which is to be exerted between the outer end of the extension 18 and the diaphragm 21, thereby delicately to adjust the tension of 45 the diaphragm to adjust its vibration. The outer end of the pipe portion 18 is desirably rounded in cross section as indicated clearly in Figs. 3 and 4 so that there is a smooth rounded edge or lip pressed against the dia- 50 phragm by a pressure which is regulated by the turning of the cap 19 by means of the knurled flange 20. By this mechanism the diaphragm 21 may be caused to vibrate as desired. The diaphragm 21 is a thin mem- 55 brane generally of delicate material and has therefore to be protected by some device such as a cap 23 threaded upon the base portion of the element 17, this cap having an opening through which sound waves may 60 pass. The delicate diaphragm is prevented from being injured by the temperature of the hand of the adjuster if the knurled flange 20 is alone engaged for the purpose

of adjusting the diaphragm tension. Any suitable means may be employed for fastening the diaphragm in position, such, for example, as the cylindrical heads of wax 24.

In Fig. 7 I have illustrated the structure having the diaphragm 21 at the bottom of the resonating tube which is unprovided with a partition 13. It will be unnecessary to describe the structure shown in Fig. 7 as the parts illustrated at the lower portion thereof are similar to correspondingly illustrated parts in Figs. 3 and 4 and to which similar characters of reference have been applied. In the case of the structures shown in Figs. 2 and 7, the cap 23 may be in the form of a horn the better to direct the sound waves set up by the diaphragm 21.

While I have herein shown and particularly described the preferred embodiment of my invention I do not wish to be limited to the precise details of construction shown as changes may readily be made without departing from the spirit of my invention, but

Having thus described my invention I claim as new and desire to secure by Letters Patent the following:—

1. A musical instrument including a cylindrical resonating tube for receiving sound waves at one end and closed at its opposite end by a semi-globular closure, the tube being provided with a partition within the same extending longitudinally thereof, this partition terminating at the center of said closure at one end, said partition having a continuation at its other end extending transversely thereof whereby the interior of the tube is subdivided into a continuous air column of a length greater than the tube.

2. A musical instrument including a resonating tube; a smaller pipe connected with the resonating tube; a cap adjustable longitudinally of the pipe and a diaphragm carried by the cap and engaged with the outer end of the pipe and whose tension is adjusted by the adjustment of the cap upon said pipe.

3. A musical instrument including a resonating tube; a smaller pipe connected with the resonating tube; a cap in threaded connection with the pipe so as to be adjustable longitudinally of said pipe; and a diaphragm carried by the cap and engaged with the outer end of the pipe and whose tension is adjusted by the adjustment of the cap upon said pipe.

In witness whereof, I hereunto subscribe my name this twentieth day of May A. D., 1913.

JOHN C. DEAGAN.
